RAILWAY TRAFFIC CONTROLLING APPARATUS

Original Filed Feb. 7, 1927

UNITED STATES PATENT OFFICE

CHARLES C. BUCHANAN, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed February 7, 1927, Serial No. 166,408. Renewed January 28, 1930.

My invention relates to railway traffic controlling apparatus, and particularly to apparatus of the type comprising means for supplying the trackway with alternating current which is periodically varied at different frequencies, and governing means on the train selectively responsive to the frequency of such variations.

I will describe one form of railway traffic controlling apparatus embodying my invention, and will then point out the novel features thereof in claims.

The accompanying drawing is a diagrammatic view illustrating one form of railway traffic controlling apparatus embodying my invention.

Referring to the drawing, the reference characters 1 and 1^a designate the track rails of a stretch of railway track over which traffic normally moves in the direction indicated by the arrow. These rails are divided, by means of insulated joints 2, into a plurality of successive track sections only one of which, A—B, is shown complete in the drawing. Train controlling current is supplied to the rails of this section from a suitable source of energy such as an alternator G. The current supplied to the track rails by this alternator may be of a frequency of the order of the usual commercial alternating current such for example as 60 cycles or 100 cycles per second.

The supply of current to the track rails is controlled by a coding device designated in general by the reference character X and comprising a plurality of rotatable cams each designated by the reference character C with a suitable distinguishing exponent. The cams C are driven at a constant speed by a suitable motor M which is supplied with current from the alternator G. The cam C¹ is provided with a plurality of swells 8 spaced about its periphery and which swells successively engage a contact 3 to periodically close the contact as the cam C¹ is rotated. In similar manner the cams C² and C³ are provided with different numbers of swells 8 which control contacts 4 and 5, respectively. One terminal of the alternator G is constantly connected with rail 1 of section A—B,

and the other terminal of the alternator is connected with the rail 1^a through one of the contacts 3, 4, or 5, depending upon traffic conditions.

It is manifest that the alternating current supplied to the rails of the trackway by alternator G is periodically varied at the frequency of operation of the contact of the device X that is interposed between the alternator and the track rail 1^a. The coding device X may be constructed to provide variations of any reasonable frequencies, but for purposes of illustration, I will assume that the cams C are rotating at 20 revolutions per minute, that cam C¹ has 4 swells, that cam C² has 6 swells, and that cam C³ has 9 swells. The selection between the several contacts of the coding device X in accordance with traffic conditions may be accomplished in any suitable manner, such, for example, as by means of a home relay H and a distant relay L. The circuits for controlling these two relays form no part of my present invention and are omitted from the drawing for the sake of simplicity. For present purposes it is sufficient to state that home relay H is normally energized but is de-energized when a train occupies the section immediately to the right of point B. The distant relay L is also normally energized but is de-energized when a train occupies either the first or the second section immediately to the right of point B. With the apparatus thus far described, when relays H and L are both energized so that front contact 6—6^a of relay H and front contact 7—7^a of relay L are closed, current from alternator G, which current I will assume to be 100 cycles per second, is supplied to the track rails over contact 5 operated by cam C³. Under these conditions the alternating current supplied to the trackway is periodically varied at a frequency of 180 cycles per minute. Current supplied to the trackway under these conditions, I will hereinafter term the "proceed code". When relay H is energized and relay L is de-energized, the closing of back contact 7—7^b of relay L includes contact 4 controlled by cam C² in the trackway circuit and under these conditions the trackway is supplied with 100 cycle cur-

80

85

90

95

100

rent interrupted at a frequency of 120 cycles per minute; this current I shall hereinafter term the "caution code". In similar manner when relay H is de-energized, the closing of back contact 6-6^b of this relay completes a circuit from alternator G to the track rails through contact 3 operated by cam C¹. Under these conditions the trackway is supplied with 100 cycle current interrupted at a frequency of 80 cycles per minute, which current I will call the "slow code".

The train indicated diagrammatically at V is provided with governing means which is responsive to the frequency of the periodic variations in the 100 cycle current supplied to the trackway. In the present embodiment of my invention the train is provided with two magnetizable cores 11 and 11^a located in advance of the forward axle 10 and disposed in inductive relation to the two track rails 1 and 1^a, respectively. Core 11 is provided with a winding 12, and core 11^a is provided with a winding 12^a, the two windings 12 and 12^a being connected in series in such manner that the voltages induced therein by train controlling current flowing in opposite directions in the track rails at an instant are additive. Windings 12 and 12^a are connected through an amplifier 13 and a transformer Q with a polarized relay R. When train controlling current is being supplied to the trackway, pulsating energy is delivered to the primary of transformer Q at the frequency of the periodic variations in such trackway current. For each impulse of energy supplied to transformer Q, during the increases of such current, an impulse of one relative polarity is supplied to relay R and during the decrease of such current, an impulse of the opposite relative polarity is supplied to the relay. The relay R is responsive to the relative polarity of the current supplied thereto and it follows that when the train controlling current supplied to the trackway is being periodically varied, the relay R is operated to close its normal and reverse contact 15-15^a and 15-15^b alternately at a frequency which corresponds to the frequency of the variations of the trackway current. Associated with relay R is a transformer T comprising a primary 16 and a secondary 17. Direct current is supplied to the primary 16 of transformer T from a suitable source of energy such as a battery D, and the polarity of such current is periodically reversed in accordance with the frequency at which relay R operates. As shown in the drawing, when relay R is energized in one direction to close contact 15-15^a, current flows from battery D through the lower half of primary 16 in one direction, and when relay R is energized in the opposite direction, current flows from battery D, over contact 15-15^b of relay R, through the upper half of primary 16 in the opposite direction. It follows that when re-

lay R is operated intermittently, the current in primary 16 of transformer T is periodically reversed at the same frequency as the periodic variations in the 100 cycle current supplied to the trackway. As a result of this periodic current in the primary of transformer T there is induced in the secondary 17 an alternating electromotive force of a corresponding frequency, which electromotive force is applied to a plurality of devices which are selectively responsive to the frequency of the current supplied thereto. As shown in the drawing a plurality of rectifiers, each designated by the reference character J with a suitable distinguishing exponent, are connected in parallel with secondary 17. Rectifier J³ supplies energy to a relay K³, and rectifiers J¹ and J² supply energy to relays K¹ and K². The rectifier J¹ is connected directly with the secondary 17, but the circuits for rectifiers J² and J³ each contain a condenser 19 and a reactor 18. The circuit which supplies energy to relay K³ is tuned to resonance at a frequency of 180 cycles per minute and the circuit over which current is supplied to K² is tuned to resonance at a frequency of 120 cycles per minute. Relays K² and K³ are each arranged to be energized only when transformer T is delivering current of the frequency to which the circuit associated with such relay is tuned.

In explaining the operation of the apparatus as a whole, I will first assume that relays H and L are both energized as shown in the drawing, so that current is being supplied to the trackway over contact 5 controlled by cam C³. The proceed code thus supplied to the trackway causes relay R to operate at a frequency of 180 cycles per minute and an electromotive force of the same frequency is induced in secondary 17 of transformer T. The current supplied to relay K¹ under these conditions energizes the relay, and since the circuit for rectifier J³ is tuned to resonance at the frequency of the current now supplied to it, relay K³ is also energized. The circuit including rectifier J² is detuned, however, at 180 cycles per minute, so that relay K² is de-energized. Under these conditions current flows from battery D over front contact 24-24^a of relay K¹, back contact 25-25^b of relay K² and front contact 26-26^a of relay K³ to the lamp 20, thereby lighting this lamp to indicate proceed.

I will next assume that relay H is energizer but that relay L is de-energized as by the presence of a train in the second section to the right of point B. Under these conditions current is supplied to the track rails in accordance with the caution code and relay R operates at a frequency of 120 cycles per minute. The current delivered by secondary 17 of transformer T therefore energizes relay K¹ as before, and relay K² is now energized because this relay is tuned to

the frequency of the current supplied thereto, but relay K^3 is de-energized because its circuit is detuned at 120 cycles per minute. Current from battery D therefore flows over front contact 24—24^a of relay K^1 and front contact 25—25^a of relay K^2 to lamp 21, thereby lighting this lamp to indicate caution.

In similar manner if relay H is de-energized, as by the presence of a train in the section immediately to the right of point B, section A—B is supplied with current in accordance with the slow code and relay R operates at a frequency of 80 cycles per minute. At this frequency relays K^2 and K^3 are both 15 detuned so that these relays are de-energized, but relay K^1 is energized. Current therefore flows from battery D over front contact 24—24^a of relay K^1 , back contact 25—25^b of relay K^2 and back contact 26—36^b of relay 20 K^3 to lamp 22, thereby displaying a slow indication on board the train.

If section A—B were occupied by a second train located between train V and point B, train controlling current would be shunted 25 away from train V by the wheels and axles of such second train. As a result, relay R would be continuously de-energized. If, for this reason or for any other reason, relay R should fail to operate intermittently, the supply of 30 energy to all the rectifiers J would be discontinued, and under such conditions relays K would all be de-energized. Current from battery D would then flow over back contact 24—24^b of relay K^1 to lamp 23, thereby lighting 35 this lamp to indicate stop.

One feature of my invention is the provision of means for supplying the trackway with alternating current of commercial frequency periodically varied at comparatively 40 low frequencies of the order from 60 to 180 cycles per minute, together with train carried apparatus including resonant electric circuits which are tuned directly to the frequencies at which the trackway current is 45 interrupted for selecting between the various codes.

In this application I have disclosed apparatus which utilizes only three different codes, but it should be particularly pointed 50 out that my invention is not limited to this number of codes but that the equipment could be expanded to provide additional code frequencies and additional tuned circuits on the train to select between such additional frequencies.

Although I have herein shown and described only one form of railway traffic controlling apparatus embodying my invention, it is understood that various changes and 60 modifications may be made therein within the scope of the appended claims without departing from the spirit and scope of my invention.

Having thus described my invention, what I claim is:

65 1. Railway traffic controlling apparatus

comprising means for supplying alternating current of commercial frequency to the trackway, means for periodically varying such current at 80, 120 or 180 cycles per minute according to traffic conditions, a train carried 70 transformer, means for supplying the primary of the transformer with periodic current of the same frequency as the variations in the trackway current, a first rectifier connected directly with the secondary of the 75 transformer, a second rectifier connected with the secondary through a circuit tuned to resonance at 120 cycles per minute, a third rectifier connected with the secondary through a circuit tuned to resonance at 180 cycles per minute, three relays, one connected with the output circuit of each rectifier, and governing 80 means selectively controlled by the three relays.

2. Railway traffic controlling apparatus 85 comprising means for supplying the trackway with alternating current of commercial frequency, means for periodically varying such current at 80 or 120 cycles per minute according to traffic conditions, a train carried 90 transformer, means for supplying the primary of the transformer with periodic current of the same frequency as the variations in the trackway current, a first rectifier connected directly with the secondary of the 95 transformer, a second rectifier connected with the secondary through a circuit tuned to resonance at 120 cycles per minute, two relays, one connected with the output circuit of each rectifier, and governing means selectively 100 controlled by the two relays.

3. Railway traffic controlling apparatus 105 comprising means for supplying the trackway with alternating current of commercial frequency, means for periodically varying such current, a train carried transformer, means for supplying the primary of the transformer with periodic current of the same frequency as the variations in the trackway current, a first rectifier connected directly with the secondary of the 110 transformer, a plurality of other rectifiers connected with the secondary through circuits tuned respectively to resonance at such frequencies, a plurality of relays, one connected with the output circuit of each rectifier, and governing means selectively 115 controlled by the three relays.

In testimony whereof I affix my signature.
CHARLES C. BUCHANAN.
